United States Patent Office

Des. 202,333
Patented Sept. 21, 1965

202,333

RESTAURANT BUILDING

Eldon C. Davis, Los Angeles, Calif., assignor to By The Numbers, Inc., Fort Wayne, Ind., a corporation of Indiana

Filed Sept. 28, 1964, Ser. No. 81,902

Term of patent 14 years

(Cl. D13—1)

FIG. 1

Des. 202,333

FIG. 4

The dominant features of my design reside in the portions shown in full lines. The platform shown in broken lines in FIGURE 1 is disclosed for illustration purposes only.

I claim:

The ornamental design for a restaurant building, as
